UNITED STATES PATENT OFFICE

2,271,484

HEAT EXCHANGER APPARATUS

Robert M. Joyce, Greenville, Miss.

Application March 6, 1940, Serial No. 322,602

1 Claim. (Cl. 126—109)

My invention relates to improvements in heat exchangers, and particularly to an arrangement of this character for heating air by passing the air to be heated through tubes to which are applied the products of combustion of an oil or the like burner, and/or the products of combustion or exhaust of a Diesel engine or the like, and an important object of my invention is to provide a simple and efficient arrangement of this character.

Another important object of my invention is to provide an arrangement of the character indicated which is especially adapted to economically provide hot air for use in cotton drying apparatus, the said arrangement being of a muffle type refractory material furnace capable of withstanding high temperatures, and providing the following specific advantages:

(1) A higher degree of efficiency at a lower operating cost.

(2) Low static pressure due to the unrestricted flow of air therethrough, thereby reducing the power requirements on the fan.

(3) Heats a larger volume of air traveling at a higher velocity than present related devices.

(4) In utilizing the heat provided by the hot water from an internal combustion engine, the cost of heat source is substantially reduced.

(5) Positive prevention of mixing and contact of the air to be heated with the products of combustion of the burner, thereby eliminating any possibility of sparks getting into the cotton when the device is used for supplying hot air to a cotton drying apparatus, thereby eliminating all fire hazard from this source.

(6) The elimination of water for heating or other purposes, thereby preventing corrosion and other deterioration of the parts due to this agency.

(7) The elimination of any moving parts subject to wear, and

(8) The complete automatic control of the temperature provided, through adaptability for complete thermostatic control in accordance with the moisture content of the cotton or the like to be dried.

Other important objects and advantages of my invention will be apparent from a reading of the following description taken in connection with the drawings, wherein for purposes of illustration I have shown preferred embodiments of my invention.

In the drawings:

Figure 1 is a general side elevational view of an embodiment of the invention employing both

oil burner and internal combustion engine cooling system radiator, as heat sources.

Figure 2 is an enlarged vertical longitudinal sectional view taken through Figure 1.

Figure 3 is a transverse vertical sectional view taken through Figure 2 approximately centrally.

Figure 4 is a view similar to Figure 1 of a modified form of the invention in which the internal combustion engine cooling system radiator is absent.

Figure 5 is a fragmentary perspective view showing the arrangement of the bricks.

Referring in detail to the drawings, and particularly to Figure 2, the numeral 5 generally designates a concrete slab supported upon a surface 6. From the concrete slab 5 rise the two laterally spaced opposite walls 7 and 8 of the exchanger which are substantially parallel and have the lower ends thereof connected by a bottom plate 9 and the end edges thereof connected by end plates 10 and 11, the walls 7 and 8 extending to an elevation above the end walls 10 and 11 as is evident from Figures 2 and 3 of the drawings. The ends of the casing comprised by

25 the side walls 7 and 8 are tapered as indicated by the numerals 12a and 13a in the embodiment shown in Figure 4, but only at the end 12 in the embodiment shown in Figure 2, with a cellular hot water radiator 14 across the tapered portion

30 13a in the embodiment of Figure 2. The radiator has upper and lower pipes 15 and 16 leading thererrom for connection to the cooling system of a Diesel engine or other internal combustion engine which while in operation will supply hot water to the radiator. The end 12 of the casing has a flange 17 connected with a flange 18 on a tapering conduit 19, while the corresponding portion of the opposite end of the casing has a tapering conduit 20 which has a flange 21 connected to

40 the radiator structure. Above the level of the radiator the casing has laterally inwardly inclining walls 21 and 22 which extend from the upper ends of the walls 7 and 8, and also longitudinally inwardly inclining walls 23 and 24 which run from the upper ends of the portions 12 and 13, the walls 21 and 22 and 23 and 24 converging to merge into the neck 25 which has a flange 26 to which is connected the flange 21 on the stack 28.

Plate-like extensions 29 and 30 rising above the upper ends of the end walls 10 and 11 and situated in the portions 12 and 13 are perforated in vertical and longitudinal rows as indicated in Figure 3 of the drawings to receive the ends of

air conveying and heating tubes 31 which open through the plates 29 and 30, respectively, so as to pass the air entering the conduit 20 through the casing and to the air outlet conduit 19 without any contact with the products of combustion rising around the tubes 31 from the furnace section of the device which is positioned below the tubes 31.

The furnace section of the device is composed of the firebrick lining 32 which lines the bottom 9, the end walls 10 and 11 and the lower portions of the side walls 7 and 8 to a point just below the lowermost of the tubes 31. Resting on the bottom 9, or rather on the lining thereon, is the assembly composed of the vertically staggered bricks 33 which form perforate side and end walls, in a rectangular shape, and act as supports for the refractory tile top 34 which protects the lower tubes 31 from direct contact of the flame coming through the burner opening 35 which is formed in the end wall 11, and through which an oil burner or the like is to be projected. The plate 34 is perforated at suitable intervals as indicated by the numeral 36.

In the above described embodiment of the invention the oil burner or the like may be operated simultaneously as a heat source with the radiator 30 into which the hot water from the cooling system of the Diesel engine or other internal combustion engine enters by the pipe 15 and leaves by the pipe 16, so that two sources of heat are applied to heating of the air entering the conduit 20 in passing through the radiator 14 and through the tubes 31, to reach the conduit 19. Midway between the ends of the tubes 31 is a heat dividing wall 37 which acts not only as an additional support for the tubes 31, but acts as a baffle to prevent concentration of the heat at any point in the casing, while providing for an even distribution of the heat rising through the casing with respect to the stack 28 which contains a thermostatically controlled damper 28', to provide automatic control of the burner which heats the burner section.

Referring now to the embodiment of the invention shown in Figure 4, this is similar in all respects to the embodiment above described except that the tapering casing end portion 13a is

present and the water radiator 14 is absent. Otherwise the structure and arrangement of the two embodiments is similar.

This application is a continuation in part of my copending application Serial No. 262,524, filed March 17, 1939, for Heat exchanger.

Although I have shown and described herein preferred embodiments of my invention, it is to be definitely understood that I do not desire to limit the application of the invention to the precise structural and functional details disclosed, except as may be required by the scope of the subjoined claim.

Having described the invention, what is claimed as new is:

15 Heating apparatus comprising a casing, cool air inlet and heated air outlet conduits connected to opposite ends of the upper part of said casing, respective headers supported across the mouths 20 of said conduits, said headers being formed with matching multiplicities of holes with horizontal air heating tubes arranged with their opposite ends inserted in aligned ones of the holes, each of said tubes thereby providing communication 25 between the inlet conduit and the outlet conduit, a vertical partition provided with holes passing all of said tubes, said partition being located substantially midway between said headers, a previous wall structure forming a combustion compartment in said casing below said tubes and said partition, a burner opening at one end of said compartment below the tubes whereby heating gases may enter said compartment from one 30 end and take a generally horizontal path across 35 said compartment before rising around said tubes, said casing having its top sloping upwardly and inwardly from its edges to the center, a stack connected with the said central portion of the top, with the vertical partition extending 40 across the casing below the central portion of the stack, said stack and said vertical partition acting to segregate portions of the heating gases along the tubes on opposite sides of the partition whereby air passing through said tubes from said 45 inlet conduit to said outlet conduit is uniformly heated.

ROBERT M. JOYCE.
